MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,378,916.

Specification of Letters Patent.

Patented May 24, 1921.

Application filed March 19, 1920. Serial No. 367,038.

To all whom it may concern:

Be it known that I, MELVIN L. STONE, a citizen of the United States, residing at Lawrence, in the county of Essex and State 5 of Massachusetts, have invented an Improvement in Feeler Mechanisms for Looms, of which the following description, in connection with the accompanying drawings, is a specification, like characters on 10 the drawings representing like parts.

This invention relates to feeler mechanisms for looms, through the agency of which filling is replenished from time to time.

15 The new feeler mechanism includes two feelers, one of which is a penetrating and the other an impinging feeler, and the two feelers are connected so that the impinging member may be moved rearwardly by the 20 frontward movement of the penetrating member when filling is substantially exhausted on a detecting beat. The rearward movement of the impinging feeler by the 25 penetrating feeler, under the conditions stated, is utilized in the present invention to effect replenishment of filling through a train of mechanism of any usual or well known character.

In the drawings:—

30 Figure 1 is a perspective view showing a feeler mechanism embodying the present invention, some of the parts being broken away;

35 Fig. 2 is a plan view showing the action of the feeler mechanism when a working supply of filling is present in the shuttle on a detecting beat; and

40 Fig. 3 is a view similar to that of Fig. 2, but illustrating the operation of the feeler mechanism when the filling is substantially exhausted.

45 The impinging feeler is provided with a blunt end portion to contact with a surface within the shuttle on a detecting beat, and the penetrating member is provided with a point or tooth which enters the filling mass on a detecting beat when a working supply of filling is present in the shuttle and meets the surface of the bobbin or 50 filling carrier when the filling is substantially exhausted. The connection between the feelers, whereby frontward movement of the penetrating feeler effects rearward movement of the impinging feeler when

filling is substantially exhausted on a detecting beat may be variously contrived, but is preferably formed of a simple lever mechanism for transmitting frontward movement of the penetrating feeler to the impinging feeler and cause its rearward movement. The two feelers are mounted on a feeler carrier which is movable toward and from the front of the loom under the frontward pressure or push against the feelers on each detecting beat. The carrier may 65 be of suitable construction, two of such general types of carriers being now well known in the art—one a swinging carrier and the other a sliding or reciprocating carrier connected to the loom frame. 70

In the present instance of the invention, the feeler carrier is formed as a slide 1 having frontwardly-extending portions 2 which are guided in a feeler stand 3 for reciprocating movement toward and from the front 75 of the loom. A spring 4 normally acts upon the feeler carrier to maintain it in its rearward feeling position, but yields frontwardly, as usual in this type of feeler carrier, to permit frontward movement of 80 the feeler carrier under the frontward pressure as the lay beats up.

The feeler stand 3 is provided with the guide 5 into which extends the end 6 of a transmitter which acts as usual in this 85 class of looms, to set in operative condition a train of mechanism for effecting replenishment of filling when the transmitter is moved frontwardly on a detecting beat.

Pivotedly mounted on the feeler carrier 90 at 7 is the actuator 8, the front end portion of which at 9 is normally held in raised or inoperative position by a yielding pin 10, but which may be depressed at times into the plane of the transmitter to engage and move the latter frontwardly on a detecting beat.

The actuator 8 is provided with a guide-way 11 in which is adjustably mounted the cam block 12 which may be secured in adjusted position by a set screw 13 or other appropriate means. The under surface of the cam block 12 is inclined downwardly and rearwardly as indicated at 14.

The rear end portion of the feeler carrier 105 1 has mounted on it the two feelers, one the impinging and the other the penetrating feeler. In the present instance, the rear

end portion of the feeler carrier is cut away at 15 to provide the legs or supports 16 and 17 for the two feelers, as will more fully appear.

5 The penetrating feeler 18 is mounted on the leg or support 16 and is guided for movement relative to the support. In the present instance of the invention, the support 16 has rising therefrom the front and rear guides or bearings 19 and 20, in which the penetrating feeler 18 is mounted for reciprocating movement relative to the feeler carrier and toward and from the front of the loom. The penetrating feeler 18 has a shouldered portion 21, between which and the front bearing 20 is interposed the spring 22, the construction being such that the spring normally acts to hold the penetrating feeler in its rearward feeling position, substantially as indicated in Fig. 1, with the shoulder or stop 21 bearing against the front surface of the rear bearing 19.

25 The rear end portion of the penetrating feeler is provided with a cap or block 23 which may be secured thereto in appropriate manner, or formed integral therewith, and projecting from the rear face of the block 23 is the point or penetrating portion 24 of the feeler. Upon forward pressure against the penetrating feeler 18, either by engagement of the filling with the rear face of the cap or block or by impingement of the surface of the filling carrier or bobbin against the penetrating point 24, the penetrating feeler 18 will be moved forwardly until the front face of the cap or block 23 meets the rear face 25 of the leg or support 16, whereupon the feeler carrier itself will be moved forwardly under the forward pressure.

45 The leg or support 17 is provided with a suitable guideway for the impinging feeler which permits the impinging feeler to be moved forwardly relative to the feeler carrier under the forward push or pressure exerted upon it. In the present instance, the guide is formed as a casing 26 in which the impinging feeler 27 is mounted for reciprocating movement. The impinging feeler 27 has a socketed portion 28 in which is seated the spring 29, the rear end 30 of which bears upon a shoulder 31 formed on the impinging feeler and the front end portion 32 of which bears against a block 33 guided for movement in the socketed portion 28 of the impinging feeler. The block 33 is pivotally connected at 34 to one arm of the lever 35 pivotally mounted at 36 upon the feeler carrier. The other end of the lever 35 is pivotally connected at 37 to the penetrating feeler, the construction being such that relative forward movement of the penetrating feeler transmits through the lever 35 a rearward movement of the im-

pinging feeler, such rearward movement of the impinging feeler being of a yielding character due to the spring 29.

70 The rear end of the impinging feeler is constituted by a shoe 38 which has a flat engaging rear surface and is adjustably connected by a bolt 39 with the main body of the impinging feeler. A slot 40 permits adjustment of the end of the impinging feeler to suit conditions of use.

75 The impinging feeler 27 has a frontwardly-extending arm 41, the front end portion 42 of which is provided with a cam surface 43 which is complementary or reverse to the cam surface 14 on the block 12 of the actuator, the construction being such that should the impinging feeler be moved rearwardly on the feeler carrier, the coaxing cam surfaces 14 and 42 will cause the actuator 8 to be turned into operative relation 80 with the transmitter 6 and effect movement thereof as the feeler carrier moves frontwardly on a detecting beat. The shuttle, which is of usual construction and consequently not shown, carries the usual filling carrier or bobbin 44 on which is wound the filling 45. When a working supply of filling is present on a detecting beat, the filling mass first engages the penetrating feeler and the point or penetrating portion 24 thereof sinks into the filling mass until the filling engages the rear face of the cap or block 23 of the penetrating feeler, whereupon the impinging feeler is moved frontwardly until the front face of the cap or block 23 meets the shoulder 25 of the support 16. The forward movement of the penetrating feeler thus transmitted to it by forward pressure of the filling mass, turns the lever 34 upon its pivotal support 100 95 and tends to move the impinging feeler forwardly. Owing, however, to the presence of a working supply of filling, the engaging face of the impinging feeler contacts with the filling mass and the movement 105 of the lever 34 is absorbed in compression of the spring 29, both the impinging and penetrating feelers thereupon moving forwardly in substantially unaltered relation with the feeler carrier. When, however, the filling has become substantially exhausted 110 on a detecting beat, as indicated in Fig. 3, the penetrating point 24 of the penetrating feeler engages the dense surface of the bobbin, and the block 23 of the penetrating member is held spaced from the bobbin or substantially exhausted filling thereon, a distance equal to the extension of the point 24 beyond the rear face of the cap or block 23; and the penetrating feeler is moved 120 forwardly until the front face of the cap or block 23 engages the rear face 25 of the support 16. The forward movement of the penetrating feeler under the conditions stated, is transmitted through the lever 34 125 130

to the impinging feeler, which, being unrestrained by the presence of filling on the bobbin, moves rearwardly until the surface 37 of the impinging feeler comes into alignment with the end or point of the penetrating portion 24 of the penetrating member. The amount of rearward movement of the impinging feeler due to the forward movement of the penetrating feeler, is dependent 5 upon the extent of rearward projection of the penetrating point 24 beyond the rear face of the cap or block 23. This amount of rearward movement of the impinging feeler serves to move the arm 40 thereof in a rearward direction and cause the cam 42 to turn the actuator into its operative position relative to the transmitter 6 so that on further forward movement of the feeler carrier 10 due to the forward pressure, filling replenishment will be effected.

What is claimed is:—

1. In a feeler mechanism for looms, the combination of a feeler carrier mounted for movement toward and from the front of 25 the loom and having rearwardly extending legs or supports, a penetrating feeler member mounted on one of the legs or supports and provided with a cap or contact portion having a rearwardly extending penetrating 30 point, an impinging feeler mounted on another of the legs or supports and having an impinging rear end, a lever pivotally mounted on the feeler carrier and connected to the two feelers to cause rearward movement of the impinging feeler by forward movement of the penetrating feeler when the filling is substantially exhausted on a 35 detecting beat, an actuator on the feeler carrier, and a cam between the actuator and impinging feeler to operatively position the actuator for effecting replenishment of filling when the impinging feeler is moved rearwardly by forward movement of the penetrating feeler on a detecting beat.
2. In a feeler mechanism for looms, the combination of a feeler carrier mounted for movement toward and from the front of the loom and having rearwardly extending legs or supports, a penetrating feeler member 40 mounted on one of the legs or supports and provided with a cap or contact portion having a rearwardly extending penetrating point, an impinging feeler mounted on another of the legs or supports and having an impinging rear end, a lever pivotally mounted on the feeler carrier between the two feelers and connected to the two feelers to cause rearward movement of the impinging feeler by forward movement of the penetrating feeler when the filling is substantially exhausted on a detecting beat, an actuator on the feeler carrier, and a cam between the actuator and impinging feeler to operatively position the actuator for effecting replenishment of filling 45 when the impinging feeler is moved rearwardly relative to the penetrating feeler an abnormal amount.
3. In a feeler mechanism for looms, the combination of a feeler carrier, a filling penetrating feeler and a filling impinging feeler both mounted on the feeler carrier in position to enter the shuttle on a detecting beat, means normally acting to hold the feeler carrier in rearward position, an actuator mounted on the feeler carrier and movable relative to the carrier from an inoperative 50 to a filling replenishing position, connections between the two feelers for effecting rearward movement of the impinging feeler.
4. In a feeler mechanism for looms, the combination of two feelers supported to enter the shuttle on each detecting beat, one having a rearwardly extending point to sink into the filling mass on a detecting beat until 55 the filling is substantially exhausted and to then be engaged by the filling carrier, and the other having a blunt impinging end which engages the filling on a detecting beat, and connections between the two feelers for effecting rearward movement of the impinging feeler into engagement with the filling when the penetrating point of the other feeler penetrates the filling on a detecting beat, and an additional movement of 60 the impinging feeler rearwardly when the penetrating point is struck by the more dense substance of the filling carrier on a detecting beat.
5. In a feeler mechanism for looms, the combination of an impinging feeler and a filling penetrating feeler, separate means for yieldingly urging each of the feelers rearwardly, connections between the feelers for placing the impinging feeler under the control of the penetrating feeler, said impinging feeler constructed and arranged to be held upon a detecting beat from moving rearwardly a relatively abnormal amount when the penetrating feeler penetrates the filling and to be moved rearwardly a relatively abnormal amount upon failure of the penetrating feeler to penetrate a surface within the shuttle on a detecting beat, and means for effecting replenishment of filling 65 when the impinging feeler is moved rearwardly relative to the penetrating feeler an abnormal amount.
6. In a feeler mechanism for looms, the combination of a feeler carrier, an impinging feeler and a filling penetrating feeler both mounted on the feeler carrier in position to enter the shuttle on a detecting beat, means normally acting to hold the feeler carrier in rearward position, an actuator mounted on the feeler carrier and movable relative to the carrier from an inoperative 70 to a filling replenishing position, connections between the two feelers for effecting rearward movement of the impinging feeler.

moved rearwardly by forward movement of the penetrating feeler on a detecting beat.

3. In a feeler mechanism for looms, the combination of a feeler carrier, a filling penetrating feeler and a filling impinging 70 feeler mounted for movement upon the feeler carrier and both of which enter the shuttle on a detecting beat, a spring acting normally to hold the penetrating feeler rearwardly and the impinging feeler forwardly on the feeler carrier, and connections between the two feelers for causing forward movement of the penetrating feeler to effect rearward movement of the filling impinging feeler.

4. In a feeler mechanism for looms, the combination of two feelers supported to enter the shuttle on each detecting beat, one having a rearwardly extending point to sink into the filling mass on a detecting beat until 80 the filling is substantially exhausted and to then be engaged by the filling carrier, and the other having a blunt impinging end which engages the filling on a detecting beat, and connections between the two feelers for effecting rearward movement of the impinging feeler into engagement with the filling when the penetrating point of the other feeler penetrates the filling on a detecting beat, and an additional movement of 85 the impinging feeler rearwardly when the penetrating point is struck by the more dense substance of the filling carrier on a detecting beat.

5. In a feeler mechanism for looms, the combination of an impinging feeler and a filling penetrating feeler, separate means for yieldingly urging each of the feelers rearwardly, connections between the feelers for placing the impinging feeler under the control of the penetrating feeler, said impinging feeler constructed and arranged to be held upon a detecting beat from moving rearwardly a relatively abnormal amount when the penetrating feeler penetrates the filling and to be moved rearwardly a relatively abnormal amount upon failure of the penetrating feeler to penetrate a surface within the shuttle on a detecting beat, and means for effecting replenishment of filling 90 when the impinging feeler is moved rearwardly relative to the penetrating feeler an abnormal amount.

6. In a feeler mechanism for looms, the combination of a feeler carrier, an impinging feeler and a filling penetrating feeler both mounted on the feeler carrier in position to enter the shuttle on a detecting beat, means normally acting to hold the feeler carrier in rearward position, an actuator mounted on the feeler carrier and movable relative to the carrier from an inoperative 95 to a filling replenishing position, connections between the two feelers for effecting rearward movement of the impinging feeler.

relative to the feeler carrier by frontward movement of the penetrating feeler on a detecting beat, and means for operatively positioning the actuator by rearward movement 5 of the impinging feeler to effect replenishment of filling.

7. In a feeler mechanism for looms, the combination of a feeler carrier, an impinging feeler and a filling penetrating feeler 10 movably mounted on the feeler carrier, means for yieldingly urging each of said feelers rearwardly, a lever pivotally mounted on the feeler carrier and operable to transmit frontward movement of one of said feelers into rearward movement of the other feeler, said penetrating feeler operable upon a detecting beat when filling is substantially exhausted to impart an abnormal rearward movement to the impinging feeler, 15 and means operable by said abnormal movement of the impinging feeler to effect replenishment of filling.

8. In a feeler mechanism for looms, the combination of a feeler carrier, an impinging feeler and a filling penetrating feeler 20 movably mounted on the feeler carrier, means for yieldingly urging each of said feelers rearwardly, means operable to transmit rearward movement of one of said feelers into frontward movement of the other feeler, said penetrating feeler operable upon a detecting beat when filling is substantially exhausted to space the feeler carrier from the substantially exhausted filling a relatively 25 abnormal distance to permit an abnormal rearward movement of the impinging feeler, and means operable by said abnormal movement of the impinging feeler to effect replenishment of filling.

40 9. A feeler mechanism comprising, in combination, a filling impinging feeler, a filling penetrating feeler adapted to penetrate the filling on a detecting beat when a working supply of filling is present and to engage the filling carrier without penetrating the carrier when the filling is substantially exhausted, a train of mechanism between the two feelers which effects rearward movement of one by frontward movement of the other on a 45 detecting beat, and means under the control of one of the feelers and movable thereby from an inoperative to an operative position, said means being positioned to effect replenishment of filling when its controlling feeler is moved rearwardly on a detecting beat a relatively abnormal amount.

60 10. In a feeler mechanism for looms, the combination of a feeler carrier, a penetrating and an impinging feeler mounted for frontward and rearward movements on the carrier and both positioned to enter the shuttle on a detecting beat, an actuator movably mounted upon the carrier, connections 65 between the penetrating and impinging feelers for causing frontward movement of

the penetrating feeler to effect rearward movement of the impinging feeler, and an arm moved relative to the actuator by rearward movement of the impinging feeler to position the actuator for replenishing filling. 70

11. In a feeler mechanism for looms, the combination of a filling penetrating feeler, an impinging feeler, connections between the two feelers causing frontward movement of the one to effect rearward movement of the other on each detecting beat, a spring normally projecting the penetrating feeler and retracting the impinging feeler, and means for effecting replenishment of filling when the impinging feeler is moved rearwardly 80 an increased amount by the frontward movement of the penetrating feeler due to substantial exhaustion of filling on a detecting beat.

12. A feeler mechanism, comprising a filling penetrating feeler and an impinging feeler, connections between the two feelers including spring means which normally acts through the connections to project the penetrating feeler rearwardly and retract the impinging feeler frontwardly and yields to permit frontward movement of the penetrating feeler to effect rearward movement of the impinging feeler a predetermined amount on a detecting beat when a working supply of filling is present in the shuttle and an increased amount when the filling is substantially exhausted on a detecting beat. 90

13. In a feeler mechanism for looms, the combination of an impinging and a filling 100 penetrating feeler both mounted to enter the shuttle on a detecting beat, connections between the two feelers for transmitting frontward movement of one into rearward movement of the other including a spring in the train of connections, said spring operable upon a detecting beat when filling is substantially exhausted to impart an abnormal rearward movement to the impinging feeler, and means operable by said abnormal movement of the impinging feeler to effect replenishment of filling. 110

14. In a feeler mechanism for looms, the combination of a feeler carrier, an impinging feeler and a filling penetrating feeler movably supported by the feeler carrier, means for yieldingly urging each of the feelers rearwardly upon the carrier, said penetrating feeler operable upon a detecting beat when filling is substantially exhausted to space the feeler carrier from the substantially exhausted filling an abnormal distance to permit an abnormal rearward movement of the impinging feeler, and means operable by the abnormal rearward movement of the impinging feeler to effect replenishment of filling. 120

In testimony whereof, I have signed my name to this specification.

MELVIN L. STONE.
